UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed May 4, 1927. Serial No. 188,670.

This invention relates to car roofs of the all-steel type, wherein metal roof sheets extend from side to side of the car and are secured to each other and to the car sub-structure to form a load sustaining structure.

One of the principal objects of the present invention is to produce a roof of the above type whose sheets have portions that cooperate with the carlines to increase the load carrying capacity of the roof and are adapted to flex or bend relative to each other and to said carlines to enable the roof sheets to accommodate themselves to the distortions of the car which occur in service. Other objects are simplicity, durability and cheapness of construction.

The invention consists principally in providing adjacent margins of the roof sheets with hollow ribs which snugly embrace each other and the carlines and have their tops permanently secured together and to the tops of the carlines and their side walls left free relative to each other and to said carlines. The invention also consists in the parts and in the arrangements and combinations of parts hereinafter described and claimed.

In the accompanying drawing, which forms part of this specification and wherein like symbols refer to like parts wherever they occur,

Fig. 1 is a plan view of a portion of a car roof embodying my invention;

Fig. 2 is a vertical transverse section through half of the roof on the line 2-2 in Fig. 1;

Fig. 3 is an enlarged vertical cross-section through one of the roof seams on the line 3-3 in Fig. 1; and

Fig. 4 is a similar cross-section through the seam at the ridge on the line 4-4 in Fig. 2.

Referring to the accompanying drawing, my invention is shown in connection with a car roof having a substructure or frame comprising Z-bar side plates 5 connected by carlines 6 of substantially inverted channel-shaped section. As shown in the drawing, the side walls of the carlines diverge from top to bottom and are provided at their lower edges with outstanding base flanges 7. The Z-bar side plates 5 are preferably arranged with their webs horizontal and with one flange projecting upwardly. The car-

lines are secured to the upstanding inner flanges of the side plates by means of suitable carline brackets in the form of angles 8 having depending flanges overlapping the upstanding flanges of the side plates and riveted or otherwise rigidly secured thereto and inwardly projecting horizontal flanges upon which the ends of the carlines are supported. As shown in the drawing, the ends of the carlines are curved downwardly at the eaves; and the surplus metal resulting from said downwardly curved ends of said carlines is utilized in widening the end portions of the base flanges 7 which are riveted or otherwise rigidly secured flatwise to the horizontal top flanges of the carline brackets 8.

Metal roof sheets 9 extend from eaves to eaves of the car and are provided along their adjacent side margins with hollow upstanding ribs 10 whose cross-sectional shape corresponds to the cross-sectional shape of the inverted channel-shaped carlines 6. The ribs at the adjacent margins of the sheets fit one over the other and over the carlines and are of such dimensions that they snugly embrace each other and the carlines. The portions of the sheets located adjacent to the lapped hollow ribs thereof are supported on the lateral base flanges 7 of the carlines; and the eaves ends of the roof sheets are supported on the tops of wooden filler blocks 11 which rest on the horizontal webs of the Z-bar side plates 5 and are rigidly secured to the outer faces of the upstanding flanges thereof. The roof sheets are preferably provided with depending eaves flanges 12 which overhang the outer faces of the wooden filler blocks 11. The eaves end portions of the overlapped side marginal ribs 10 of the roof sheets are curved downwardly and merge into the plane of the body portions of the sheets where the sheets are turned down to form the depending eaves flanges 12; and the lateral base flanges 10^a that appear at the lower edges of the eaves end portion of the outer wall of the ribs 10 is the surplus of metal resulting from the downwardly curved eaves portions of said ribs.

The ribs 10, which are of the same cross-sectional shape as the carlines, have their tops rigidly secured flatwise to each other and to the flat tops of the carlines by rows of rivets 13.

Running boards 14 extend longitudinally

of the car at the ridge and are preferably supported on and rigidly secured to the top flanges of Z-shaped running board saddles 15, whose bottom flanges are supported on 5 the flat tops of the ribs 10 and are rigidly secured in position by the securing rivets 13 therefor.

By the arrangement described, the tops 10 of the overlapped marginal ribs 10 of adjacent roof sheets are rigidly secured flatwise to each other and to the tops of the carlines 6 and thus cooperate with the carlines in increasing the load carrying capacity of the roof, while the side walls of the 15 overlapped ribs are free to move towards and away from each other and from the side walls of the carlines and thus enable the portions of the sheets located between the carlines to accommodate themselves to the 20 distortions of the car frame.

An important advantage of the foregoing arrangement is that it eliminates the use of detachable members for securing the lapped ribs to the carlines, which members are objectionable because they are liable to work loose; and it also eliminates the use of separate fastening members which serve to clamp the side walls of the ribs to the carlines and thus causes the sheets to tear when 30 the car frame distorts. It is noted as an important advantage of my invention that the hollow ribs are permanently secured to the carlines by rivets which are driven hot, which operation causes the galvanizing to 35 flow and form a weather-proof seal between the ribs and the heads of the securing rivets.

What I claim is:

1. A car roof comprising side plates connected by carlines of substantially inverted 40 channel-shaped section, and roof sheets extending from side plate to side plate and rigidly secured thereto, said roof sheets being provided along their adjacent margins with hollow ribs which embrace each other and 45 the inverted channel-shaped carlines, the tops of said ribs being rigidly riveted together and to the tops of said carlines and the sides of said ribs being left free.

2. A car roof comprising side plates con-

nected by carlines of substantially inverted 50 channel-shaped section, and roof sheets extending from side plate to side plate and rigidly secured thereto, said roof sheets being provided along their adjacent margins with hollow ribs which embrace each other 55 and the inverted channel-shaped carlines, the tops of said ribs being rigidly secured by hot driven rivets together and to the tops of said carlines and the sides of said ribs being free to yield relative to each other and 60 to the sides of said carlines.

3. A car roof comprising side plates connected by carlines of substantially inverted channel-shaped section and roof sheets extending from side plate to side plate and rigidly secured thereto, said roof sheets being provided along their adjacent margins with hollow flat-topped ribs adapted to snugly 65 embrace each other and the inverted channel-shaped carlines, the tops of said ribs being rigidly riveted together and to the tops of the carlines flatwise and the sides of said ribs being free to yield relative to each other and to the sides of said carlines.

4. A car roof comprising side plates connected by carlines of substantially inverted channel-shaped section having outstanding base flanges at the lower edges of their side walls, and roof sheets extending from side plate to side plate and rigidly secured thereto, said roof sheets being arranged with their body portions between adjacent carlines and supported on the base flanges thereof, said roof sheets having flat-topped ribs along 75 their adjacent margins adapted to embrace 80 each other and the inverted channel-shaped carlines, the tops of said ribs being permanently riveted together and to the tops of said carlines flatwise, whereby said ribs are adapted to cooperate with said carlines in 85 supporting the vertical roof load, and the sides of said ribs being free to yield relative to each other and to the sides of the carlines in response to distortions of the car frame.

Signed at New Kensington, Pennsylvania, 95
this 29th day of April, 1927.

CHARLES DAVID BONSALL.
